CLAIM

The ornamental design for an in-vehicle operating device, as shown and described.

DESCRIPTION

FIG. 1 is a perspective view of an in-vehicle operating device showing the new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines in the figures depict portions of the in-vehicle operating device that form no part of the claimed design.

The rectangular area shown in the front view is a display screen, while the six rectangular areas are push buttons and the round part is a rotary knob.
